UNITED STATES PATENT OFFICE.

EDGAR JOHN SMITH, OF CARDIFF, WALES.

LOADING HOPPER.

Application filed January 12, 1926, Serial No. 80,697, and in Great Britain April 23, 1925.

This invention relates to a hopper or receptacle for facilitating loading road or other vehicles with material in bulk from railway vehicles.

5 In unloading the contents of a railway wagon carrying material in bulk into a motor lorry, cart or other road vehicle, it is ordinarily necessary for the road vehicle to remain alongside the railway wagon the full 10 period of time occupied in shovelling a full load of the road vehicle out of the railway vehicle. This entails an uneconomical utilization of the road vehicle and frequently 15 also a waste of the time of the personnel thereof. In addition, especially in restricted spaces, the standing road vehicle is a hindrance to other road vehicles.

To avoid a road vehicle having to wait 20 alongside a railway vehicle a long time whilst being loaded with material in bulk, it has been proposed to provide a hopper or receptacle mounted on a wheeled frame which is placed alongside a railway wagon so that the contents thereof can be slowly 25 transferred by hand to the hopper. Then on a lorry arriving for a load, the contents of one or more of such already filled hoppers is discharged into the lorry which can without delay start away again.

30 Now the present invention relates to a hopper or receptacle for use under the above conditions, but which does not itself present any obstruction in the roadway alongside the rail track or siding.

35 For this purpose, the invention consists of a hopper or receptacle provided with means whereby it can be supported by a railway wagon above a road or other vehicle alongside and adapted or provided with 40 means for the controlled intermittent discharge of its contents into the alongside vehicle.

A hopper contrivance according to the invention is shown by way of example on 45 the accompanying drawing, in which:—

Fig. 1 is an end elevation, and

Fig. 2 is a side elevation of one form of construction.

50 Fig. 3 is an elevation of a modification of a supporting frame.

a represents the side of a railway wagon and *A* a lorry alongside.

A hopper bucket is supported from the side *a* of the railway wagon.

55 This hopper bucket consists of upright ends *b* and downwardly converging sides *c*

and *d*. At the lower border of the side *d* remote from the railway wagon is pivoted at its upper border a flap door *e* which opens outwards and which closes against borders 60 of the ends *b* and at its lower border against the lower border of the other side *c* of the bucket.

The flap door *e* is locked in the closed position by a sliding latch bar *f* and pivoted bell-crank latches *g* connected thereto by a slot *g*¹ on each through which passes a stud *f*¹ on the sliding bar *f*. The latch bars *g* engage in gated sockets *i* on the side *c*.

The sliding bar *f* and latches *g* are operated by a hand lever *j*¹ through a link *j*, lever *k*, transverse shaft *l*, lever *m* and link *n*.

The hopper bucket described above is supported at each end by an adjustable and collapsible bracket frame. Each bracket frame consists of a bar *o* of T-section extending downwards along the outer face of the side *a* of the railway wagon. This bar *o* is supported by a hook *p* engaged over the upper border of the side *a* of the wagon, and 80 through a T-section socket *p*¹ at the base of such hook *p* the bar *o* passes and to which it is pinned, the pin passing through a hole of a series of holes *o*¹ formed at intervals along the web of the bar *o*. To a T-section socket 85 *q*¹ which embraces the bar *o* above the socket *p*¹, is pivoted a lever arm *q* the outwardly protruding end of which is supported by a chain *r* secured respectively thereto and to the upper end of a derrick arm *s*, pivoted at 90 its lower end to a T-section bearer socket *s*¹ embracing and pinned to the downwardly extending bar *o* a suitable distance beneath the hook *p*. Each derrick arm *s* is supported by a cable *t* leading from its upper end over a sheave *t*¹ mounted coaxially on the pivot rod *q*² of the lever arm *q*. As may be seen in Fig. 2, this pivot rod *q*² extends between and interconnects the two bracket frames, each of which comprises a derrick arm *s* supporting a lever arm *q*. The lower end of each cable *t* is pinned by a shackle *t*¹ to the respective downwardly extending bar *o*.

The upper surface of the lever arm *q* of each bracket frame constitutes a track on which the bucket is supported by wheels *u* at the lower portion of the side *c*. These wheels *u* encounter curved guide stops *g*² at the outer ends of the lever arms *q* so 105 that the bucket can there tilt about the axis of the wheels *u*. The wheels *u* being set 110

back from the outer lower border of the side *c*, enhances the out-reach of the hopper. The outward tilting of the bucket is limited by a segmental bar *v* pivoted thereto and by alternative notches engaging the rod *q*², which extends between the two bracket frames. The bucket is normally linked to the supporting bracket frames by links *w* pivoted to the lever arms *q* and to the ends *b* of the bucket, the latter connection being releasable after withdrawal of a pin *w*¹ passed through the respective pivot.

During shunting operations, on release of the links *w* from the bucket, the latter bucket can be displaced along the lever arms *q* into the railway wagon. The lever arms *q* of the bracket frames can then be folded down and the derricks *s* folded up against the side *a* of the wagon, or the whole can be detached and stowed in the wagon so that are no protruding parts to foul other wagons or objects.

With the above described construction, the height of support of the bucket is, within limits, adjustable by adjusting the sockets *p*¹, *q*¹, and *s*¹ and shackles *t*¹ along the bars *o*, whilst the angle of the bucket is adjustably limited by the segmental bar *v*.

To facilitate erection of the bucket *b*, *c*, *d* and the lever arms *q* which form tracks therefor, pulley tackles *u* are provided on the derrick arms *s*, these tackles *u* being made fast after the lever arms *q* have been connected to the chains *r* from the heads of the derricks and other parts are in position. An eye *b*¹ is provided at each end of the bucket to receive the hook *u*¹ of the respective lower pulley block of the respective tackle *u*. Likewise a cleat *u*² is provided on each derrick *s* to make fast the respective tackle fall *u*.

Although the construction of supporting brackets shown in Figs. 1 and 2 permits a small degree of vertical adjustment limited by the amount the bars *o* can be raised in the hook sockets *p*¹ without jeopardizing stability, when unloading very low and shallow railway wagons it may be necessary for the bucket to be situated higher than permitted by this construction of bracket. Fig. 3 shows a construction of bracket which permits the lever arms *q*, and therewith the bucket to be raised considerably above the upper border of the side of the railway wagon. In the construction illustrated in Fig. 3, the bars *o* which extend down the side of the railway wagon are formed integrally with the hooks *p* and also extend considerably above the hooks. Each cable *t* is wrapped around a separate winding drum sheave *v* and connected to the respective lever arm *q* at the inner end thereof. The inner end of each lever arm *q* is forked and by studs *w* having anti-friction rollers engages behind flanges on the respective vertical bar *o*. The

inner end of the lever arm *q* is connected by a link *x* to the bearer *s*¹ of the respective derrick *s*. The bearers *s*¹ of the derrick arms *s* are in this construction forked to embrace the bars *o* and engage behind the flanges thereof by studs *y* having anti-friction rollers. The links *x* have holes at intervals whereby they are adjustably pinned to the respective lever arms *q* and derrick bearers *s*¹, and the vertical distance separating these parts may be adjusted. The winding drum sheaves *v* of the two brackets are keyed on a cross shaft *v*¹ and are rotated in unison by a hand crank *z* fast with a pinion *z*¹ gearing with a spurwheel *v*² fast with the cross shaft *v*¹. The two lever arms *q* in this construction are rigidly interconnected by cross rods *q*² so that they are displaced as a single structure.

The height of the brackets relatively to the railway wagon is adjusted by rotating the crank *z* to raise or lower the brackets as a whole along the bars *o*.

To strengthen the side *a* of the railway wagon from yielding outwards under the weight of the bucket hopper, more especially when such side is pivoted as a door, the hook bars *o* can be connected by tie rods (not shown) to similar hook bars clamped to the other side of the wagon.

Conveniently each hopper holds approximately one ton. Thus a four ton lorry can be driven beneath and receive on one side the contents of two hoppers. Then the lorry is turned round and driven beneath and receives on the other side the contents of two more hoppers, whereby a trimmed load is taken.

A great saving in demurrage is also effected by the use of these hoppers.

Obviously the vehicle into which the load is discharged may be a railway wagon on an adjoining track, the advantages described above in connection with a road vehicle being likewise obtained. For instance one railway wagon can be quickly loaded from filled hoppers supported on a number of other railway wagons, the wagon to be loaded being moved successively from one to another of the wagons the bulk contents of which are being shovelled into the hoppers.

I claim:

1. An arrangement for facilitating loading a vehicle from and alongside a railway wagon, consisting of a hopper bucket, means for controlling the intermittent discharge of said bucket, hooks engaging over a side of said railway wagon, lever arms supported by said hooks and supporting said bucket, and derricks supported by said hooks and extending upwards from beneath and supporting said lever arms.

2. An arrangement for facilitating loading a vehicle from and alongside a railway wagon, consisting of a hopper bucket, means

for controlling the intermittent discharge of said bucket, hooks engaging over a side of said railway wagon, bars extending downwards from said hooks, lever arms on said bars and supporting said bucket, and derricks on said bars and extending upwards from beneath and supporting said lever arms.

3. An arrangement for facilitating loading a vehicle from and alongside a railway wagon, consisting of a hopper bucket, means for controlling the intermittent discharge of said bucket, hooks engaging over a side of said railway wagon, bars extending upwardly and downwardly from said hooks, lever arms sliding along said bars and supporting said bucket, derricks sliding along said bars and extending upwards from beneath and supporting said lever arms, winding drums carried by said bars, and cables wrapping said drums and connected to the heads of said derricks and to the inner ends of said lever arms.

4. An arrangement for facilitating load-

ing a vehicle from and alongside a railway wagon, consisting of a hopper bucket, means for controlling the intermittent discharge of said bucket, lever arms supporting said bucket, means supporting said lever arms to extend from a side of said railway wagon, a rod extending between said lever arms, and a notched segmental bar on said bucket engaging said rod.

5. An arrangement for facilitating loading a vehicle from and alongside a railway wagon, consisting of a hopper bucket, means for controlling the intermittent discharge of said bucket, lever arms supporting said bucket, means supporting said lever arms to extend from a side of said railway wagon, links pivoted to said bucket and to said lever arms, a rod extending between said lever arms, and a notched segmental bar on said bucket engaging said rod.

In testimony whereof I have signed my name to this specification.

EDGAR JOHN SMITH.
